(57) **CLAIM**

The ornamental design for motor drive enclosure, as shown and described.

DESCRIPTION

This application is related to co-pending U.S. Design patent application Ser. No. 29/331,637, entitled "Motor Drive Enclosure," filed on Jan. 29, 2009, which is hereby incorporated by reference in its entirety.

FIG. 1 is a front, left side and top perspective view of a motor drive enclosure showing my new design;

FIG. 2 is a front view thereof;

FIG. 3 is a top view thereof; and,

FIG. 4 is a left side view thereof.

The broken lines in the drawings show unclaimed subject matter only, and do not form part of the claimed design.

1 Claim, 4 Drawing Sheets

FIG. 1

FIG. 2

FIG. 3

FIG. 4
